(57) **CLAIM**

The ornamental design for a chair as shown and described.

DESCRIPTION

FIG. 1 is a perspective view of a chair showing my new design;

FIG. 2 is a front view of the chair of FIG. 1.

FIG. 3 is a rear view of the chair of FIG. 1.

FIG. 4 is a left side view of the chair of FIG. 1.

FIG. 5 is a right side view of the chair of FIG. 1.

FIG. 6 is a top view of the chair of FIG. 1; and,

FIG. 7 is a bottom view of the chair of FIG. 1.

Portions of the chair shown in broken lines form no part of the claimed design.

1 Claim, 7 Drawing Sheets
